UNITED STATES PATENT OFFICE.

KARL C. J. HANSELMANN, OF BALTIMORE, MARYLAND.

SHUTTER-FASTENER.

No. 827,363.

Specification of Letters Patent.

Patented July 31, 1906.

Application filed March 2, 1906. Serial No. 303,751.

To all whom it may concern:

Be it known that I, KARL C. J. HANSELMANN, of the city of Baltimore and State of Maryland, have invented certain Improvements in Shutter-Fasteners, of which the following is a specification.

In the further description of the said invention which follows reference is made to the accompanying drawings, forming a part hereof, and in which—

Figure 1 is a perspective view of a part of the front of a building, together with parts of the window-sill, the window-frame, and one shutter, provided with the present invention. Fig. 2 is a top view of a semicircular adjustable tangentially-notched bar forming a part of the said invention. Fig. 3 is an edge view of the bar shown in Fig. 2. Figs. 4 and 5 are respectively a top and an edge view of a part of the notched bar on an enlarged scale. Figs. 6 and 7 are respectively a front and an edge view of a latch employed in connection with the said semicircular bar to hold the shutter in various positions with reference to the window-frame.

Referring now to the drawings, 1 is the front wall of a building, and 2 the window-sill. 3 is the window-frame, which is seated on the window-sill.

5 5 is a semicircular bar, which is attached at one end to the horizontal projecting part *a* of the window-frame. The other end of the said bar is free or unattached to the building.

In order that the semicircular bar 5 may be easily and readily fastened to the part *a* of the window-frame and admit of its adjustment in position without changing the situation of its attached end, or, in other words, that the said bar may be thrown around or about a central point which must be at a certain distance from the center of the pintles of the hinges, whereby the shutter is connected to the window-frame, the bar terminates in a circular disk *c*, adapted to rest in a circular depression *d* in the part *a* of the window-sill, and to allow of such adjustment the corners of the sill adjoining the said depression are cut away, as at *e*. By this arrangement it is only necessary in affixing the bar 5 to the

50 window-frame to mark on the frame a point which has a distance from the hinge-pintle equal to the radius of the semicircular bar

and then sink at that point a cavity in the frame having a diameter which is the same as that of the disk *c*. The corners, as at *e*, 55 are then cut away and the bar placed in position and held temporarily thereat by a central screw. The other end of the bar is then brought to the proper distance from the center of the pintle, after which other screws are 6c used to hold the bar in its now correct position.

The shutter, which is denoted by 7, is provided with a hole through which is inserted the free end of the semicircular bar before the same is finally secured to the frame, and over this hole is fastened a latch 9, the bolt *f* of which bears on the upper surface of the bar 5.

In order that the shutter may be held when fully open or closed or at certain intermediate points through the medium of the bolt, the bar 5 is provided with notches *g*, adapted to receive the end of the bolt *f*, and to provide for variations in the projection of the hinge-pintles beyond the radial dotted line shown in Fig. 2, which would change the angle of the notches with respect to the radial line, the sides of the notches are made curved, as shown in Fig. 4.

In the drawings the shutter is shown as in a half-open position, and it will be understood that by lifting the bolt above the surface of the bar 5 the shutter may be further opened or closed and held securely at any point at which the bolt registers with a notch, and when the shutter is closed it cannot be opened from the outside.

I claim as my invention—

In combination with a window-frame having a circular depression therein, and a shutter which is hinged to the window-frame, a fastener which consists of a semicircular notched bar which terminates at one end in a circular disk which is placed in the circular depression in the window-frame, and a latch fastened to the shutter adapted to coöperate with the said notched bar to hold the shutter in various positions, substantially as specified.

KARL C. J. HANSELMANN.
